CLAIM

The ornamental design of a dip tube paint applicator device cap, as shown and described.

DESCRIPTION

FIG. 1 is a front perspective view of a dip tube paint applicator device cap;

FIG. 2 is a top plan view of FIG. 1;

FIG. 3 is a bottom plan view of FIG. 1;

FIG. 4 is a left side elevational view with the right side being a mirrored image of FIG. 1;

FIG. 5 is a rear elevational view of FIG. 1; and,

FIG. 6 is a front elevational view of FIG. 1.

The broken line showing is included for the purpose of illustrating and forms no part of the claimed design.
